**POLE CONNECTOR FOR SHELVING, RACKS,
AND THE LIKE**

Joseph C. Putterman, 3521 Section Road,
Cincinnati, Ohio 45237

Filed Oct. 27, 1971, Ser. No. 193,238

Term of patent 14 years

Int. Cl. D8—08

U.S. Cl. D8—236

FIG. 1 is a perspective view showing my new design for a pole connector for shelving, racks, and the like.

FIG. 2 is a side elevational view.

FIGS. 3 and 4 are right and left end views, respectively.

FIG. 5 is a section on line 5—5 of FIG. 2.

I claim:

The ornamental design for a pole connector for shelving, racks, and the like, as shown.
